UNITED STATES PATENT OFFICE.

CHARLES C. REINHARDT, OF NEW YORK, N. Y.

SKATE.

SPECIFICATION forming part of Letters Patent No. 568,547, dated September 29, 1896.

Application filed October 19, 1895. Serial No. 566,247. (No model.)

To all whom it may concern:

Be it known that I, CHARLES C. REINHARDT, a citizen of the United States, residing in the city, county, and State of New York, have invented certain new and useful Improvements 5 in Skates, of which the following is a specification.

This invention has reference to certain improvements in skates of that class known as 10 "racing-skates," which, owing to the greater length of their runners, require a special construction, so as to provide for the extra pressure on the forward portion of the same.

The requirements of a racing-skate are an 15 extra length of runner combined with strength of construction and greatest possible reduction in weight, so that the skate can stand the extra strain and pressure to which it is subjected when in actual use. These requirements 20 are met by actual tests in my improved skate, which comprises a long thin runner, and a longitudinally-grooved runner-support riveted to the sole and heel parts of the foot-piece and tapering at the front end in advance 25 of the point of connection between the sole and the same. The foot-piece is provided with recesses at the under side for the straps and with a transverse strip of metal which 30 extends across the sole part of the foot-piece and is provided with prongs, said prongs forming in connection with a disk provided with a lug entering into the heel a rigid connection for the rivets that are passed from the runner-support through the foot-piece and 35 the sole-strip and heel-disk, as will be fully described hereinafter, and finally pointed out in the claims.

In the accompanying drawings, Figure 1 represents a perspective view of my improved 40 skate; and Figs. 2 and 3 are vertical transverse sections on lines 2 2 and 3 3, Fig. 1.

Similar letters of reference indicate corresponding parts.

Referring to the drawings, A represents the 45 runner of my improved skate, which runner is made of extra length, by preference from fifteen to twenty inches in length, so as to extend a considerable distance beyond the toe and heel of the foot. The runner is riveted in 50 a longitudinal groove of the runner-support B, by which it is connected to the foot-piece C. The runner-support B is preferably made of

aluminium, which, owing to its lightness and proportionate strength, is especially adapted for the extra strain and pressure to which the 55 skate is subjected when in use, as steel or any other metal by reason of its weight would not permit a practical skate for racing purposes. The runner-support B is made wider below the sole than between the sole and heel 60 connection, and tapers from such wide connected front part to its extreme front end, while at the point of connection with the heel the runner-support is also made wide, and both the wide sole part and the wide heel part 65 riveted by means of transverse rivets to the foot-piece.

The runner-support B is provided with recesses or indentations at its widest portions, so as to make the connection by means of 70 riveting-pins d d with the sole and heel parts of the foot-piece. To produce a strong connection between the runner-support and the sole part by the riveting-pins d d, the foot-piece is provided at its sole part with a transverse steel strip e, which is provided with 75 pointed prongs e', that engage with the sole of the shoe, while the heel-piece is provided with a disk f, having a headed lug f', that is adapted to engage with a recess of the heel 80 of the shoe. By means of the transverse sole-strip d and the disk-shaped heel-piece f a rigid connection between the runner-support and the sole-piece is obtained, as thereby the riveting-pins have a firm bearing and can be 85 firmly applied to the foot-piece.

The foot-piece is provided at the under side in front of the sole-piece with a recess g, and in front of the heel-piece with a recess g', through which recesses the straps by which 90 the skate is attached to the foot can be conveniently passed without requiring extra holes passing through the foot-piece or runner-support of the straps.

My improved skate combines the extra 95 length of runner with considerable strength and lightness, so that the runner is enabled to resist the extra pressure on the same without bending or breaking, the lightness of the skate being due to the use of aluminium for the 100 runner-support, so that racing-skates with runners from sixteen to twenty inches long and from one-sixteenth to three thirty-second parts of an inch can be made without

undue weight and with the required strength of the strain exerted on them.

Having thus described my invention, I claim as new and desire to secure by Letters 5 Patent—

1. In a skate, the combination of a foot-support, a longitudinally-grooved runner-support, broader at the heel and ball portions than between said portions, and having an 10 elongated front extension projecting beyond the toe of the foot-support and tapering gradually from the broadened ball portion, means for attaching said runner-support to said foot-support, and a long thin runner held in the 15 groove of said runner-support.
2. In a skate the combination of a foot-piece provided with a transverse metal strip having prongs, a heel-plate provided with an 20 upwardly-extending lug, a long thin runner extending some distance beyond the heel and

toe portions of said foot-piece, a longitudinally-grooved runner-support extending from the heel portion of said foot-piece to the tip end of the runner and made wider at the ball and heel portions than between said portions, 25 said support tapering gradually from the widened ball portion to the tip thereof, riveting-pins extending through the transverse metal strip, the foot-piece and the widened ball portion of the support, and rivets adapted 30 to clamp the heel-plate, foot-piece and the runner-support firmly together.

In testimony that I claim the foregoing as my invention I have signed my name in presence of two subscribing witnesses.

CHARLES C. REINHARDT.
